CLAIM

The ornamental design for an ankle brace, as shown and described.

DESCRIPTION

FIG. 1 is a perspective view of an ankle brace;

FIG. 2 is a left side view thereof;

FIG. 3 is a right view thereof;

FIG. 4 is a front view thereof;

FIG. 5 is rear view thereof;

FIG. 6 is a top view thereof; and,

FIG. 7 is a bottom view thereof.

It is noted that the ankle brace illustrated in the drawings is for use on a right foot and it is understood that, for an ankle brace for use on a left foot, but still in accordance with the ornamental design illustrated in the drawings, each of the respective views shown in the Figures would be a mirror image thereof.

The broken lines illustrate portions of the ankle brace which form no part of the claimed design.
